UNITED STATES PATENT OFFICE.

EDWARD A. ROBINSON, OF MONTREAL, QUEBEC, CANADA, ASSIGNOR TO HIMSELF AND ELLISON EDWARD WORKMAN, OF MONTREAL, CANADA.

AUTOMATIC TRAIN-PIPE CONNECTER.

Application filed May 13, 1921, Serial No. 469,188, and in Canada May 12, 1921.

My invention relates particularly to the buffing and shock-absorbing properties of the connector and has particular reference to the means which provides for the adjustment of the face of the connector which makes contact with a companion connector on another car, this adjustment being to effect the relative positions of the contacting face of the connector with regard to the pulling face of the car coupler. This broad idea is not claimed by me as it forms the subject matter of a pending application.

My present invention has for its object to provide a simple construction of combined buffer and shock-absorber which may be adjusted in its carrying part without in any way disorganizing or dismembering the carrying parts of the connector.

To this end the invention consists of a carrying part through which one end of a helical spring is screwed, the opposite end being rotatively connected to the connector head.

For full comprehension, however, of my invention reference must be had to the accompanying drawings in which similar reference characters indicate the same parts and wherein:

Figure 1 is a side elevation of my invention with the pulling face of a car coupler indicated diagrammatically;

Figure 2 is a transverse sectional view taken on line 2—2 Fig. 1;

Figure 3 is a vertical sectional view taken on line 3—3 Fig. 2; and

Figure 4 is a rear view of the bracket with the spring protruding through it.

The car coupler is indicated at 2 and its pulling face at 3, the bracket for supporting the connector at 4 and the connector head at 5. All these parts are and may be of well known construction and apart from combination do not enter into my invention.

According to my invention a helical spring 14 is screwed through a cylindrical opening 6 in the bracket. This cylindrical opening is of slightly less diameter than the spring and the bracket is split and provided with a clamping bolt 7. The opposite end of the spring is rotatably connected to the connector head by a yoke 9 the rear face 10 of which is annularly flat and disposed parallel to the vertical plane in which the mouths of the gaskets lie. This rear face of the yoke 9 has a rearward extension in the form of a

central hub 13 with surrounding annular shoulder. At opposite sides of the hub a pair of curved jaws 12 are positioned for the spring 14. The engaging ends of the jaws are curved inwardly as at 15 and are adapted to be moved into position gripping the spring by a clamping collar having a cylindrical portion 16 and a converging end 17 forming a concave inner face 18 conforming to the outer faces of the jaws 12. The cylindrical portion of this collar is internally screw-threaded to engage the outer circumference of the yoke which is correspondingly threaded. The forward end convolution of the helical spring 14 is set at right angles to the axis of the spring and is engaged and held rigidly in place by the jaws 15.

The object, as above stated, of my invention is to provide for the projection of the connector forwardly from the bracket by a simple means which also serves for the adjustment of the extent of projection. This is effected by the combination of parts just described, as follows: In order to set the face of the connector in the same vertical plane as the pulling face of the coupler when initially adjusting the parts the collar 16 is rotated to move its clamping end 17 away from the jaws 12, thus releasing the clamp and jaws sufficiently to permit rotation of the end convolution 20 of the spring along with the jaws after which or during which the spring 5 is screwed into the bracket. The convolution 20 of the forward end of the spring rotates in its seat along with the jaws. When the adjustment has brought the face of the connector in exact alignment with the pulling face of the coupler, most minute adjustment being capable with this means, the jaws 12 are again tightened; thus setting the head in its proper position with regard to the pulling face of the coupler.

Although I have illustrated clamping jaws 12 and collar 16 for so connecting the forward end of the spring to the head that it may be rigidly fastened and rotatable under different circumstances, any other means performing these functions may be employed without departing from the spirit of my invention; and the same can be said of the fastening of the spring in its adjusted position in the bracket 4.

What I claim is as follows:

1. In an automatic train-pipe connector of the type operating in conjunction with

and in a plane parallel to the plane of a car coupler, the combination with the connector head and means for supporting the same from the car coupler, a combined buffering and adjusting mechanism consisting of a yielding member connected at one end to the supporting means to adjust angularly with rotation of the mechanism; means for connecting the opposite end in rotatably adjustable position to the connector head with rigid immovable connection during normal operating conditions; and means for releasing the last mentioned end of the yielding member when adjustment is required.

15 2. In an automatic train pipe connector of the type operating in conjunction with and in a plane parallel to the plane of a car coupler, the combination with the connector head and means for supporting the same from the car coupler, a combined buffering and adjusting mechanism consisting of a buffer spring, means for clamping one end of the spring in the supporting means and for permitting adjustment of the spring axially with circumferential movement of the spring, means for connecting the opposite end of the buffer spring in rotatably adjustable position to the connector head with rigid immovable connection during normal operating conditions, said last mentioned means being operable to release the last mentioned end of the buffer spring when adjustment is required.

3. In an automatic train pipe connector of the type operating in conjunction with and in a plane parallel to the plane of a car coupler, the combination with the connector head and means for supporting the same from the car coupler, of a combined buffering and adjustable mechanism consisting of a buffer spring, means for clamping one end of the spring in the supporting means and for permitting adjustment of the spring axially with rotary movement, means for connecting the opposite end of the buffer spring to the connector head in rotatably adjustable position with rigid immovable connection during normal operating conditions, said last mentioned means being operable to release the last mentioned end of the buffer spring when adjustment is required while retaining the same against axial movement.

4. In an automatic train pipe connector of the type operating in conjunction with and in a plane parallel to the plane of a car coupler, the combination with the connector head and means for supporting the same from the car coupler, of a combined buffering and adjustable mechanism consisting of a buffer spring, means for clamping one end of the spring in the supporting means and for permitting adjustment of the spring axially, means for connecting the opposite

end of the buffer spring to the connector head with rigid immovable connection during normal operating conditions, consisting of a yoke carried by the connector head and having movable jaws for engaging the end convolution of the spring and a clamping member mounted adjustably upon the yoke and adapted to in different positions of adjustment clamp the jaws upon the spring and release the same respectively.

5. In an automatic train pipe connector, a bracket, a spring clamped in the lower end of the bracket to permit adjustment of the spring as a thread within the bracket, a head, a yoke carrying the head and having a flat rear face, parallel with the operating face of the head, a cooperating flat face upon the end of the spring furthest from the bracket, clamping means for holding the end of the spring in different rotary positions against the flat end of the yoke, and means for tightening and releasing the clamping means.

6. In an automatic train pipe connector, a bracket, a spring adjustable angularly and at the same time longitudinally with respect to the bracket and supported in it, forwardly projecting and having a flat front end, a head and supporting connections between the head and the spring clamping the spring in different rotary positions with respect to the head.

7. In an automatic train pipe connector, a bracket, a spring adjustable rotatably and at the same time longitudinally with respect to the bracket and supported in it, forwardly projecting and having a flat front end, a head and supporting connections between the head and the spring clamping the spring in different rotary positions with respect to the head, retaining the relative longitudinal position of the head and spring.

8. In an automatic train pipe connector, a bracket, a spring rotatable therein and axially advancing with rotation, clamping means for holding the spring, a head and supporting means for holding the head upon the spring comprising a rotatably movable clamp adapted to clamp the spring against the head in relatively differing rotary positions and a clamping nut for holding the clamp in said rotary positions.

9. In a train pipe connector, a bracket, a spring adjustable longitudinally therein, clamping means for holding the spring in adjusted position, a head and clamping means for fastening the head to the spring and permitting adjustment of the head around the axis of the spring while maintaining the adjusted forward projection of the head.

In testimony whereof I have signed my name to this specification.

EDWARD A. ROBINSON.
